UNITED STATES PATENT OFFICE.

EDMUND B. POWERS, OF NEW YORK, N. Y., ASSIGNEE TO EMPIRE RAILWAY APPLIANCE CORPORATION, OF NEW YORK, N. Y., A CORPORATION OF NEW YORK.

ANTICREEPING DEVICE FOR RAILWAY-RAILS.

1,168,672.

Specification of Letters Patent. Patented Jan. 18, 1916.

Application filed January 22, 1915. Serial No. 3,679.

To all whom it may concern:

Be it known that I, EDMUND B. POWERS, a citizen of the United States, residing in the city of New York, borough of Brooklyn, in the county of Kings and State of New York, have invented a certain new and useful Improvement in Anticreeping Devices for Railway-Rails, of which the following is a specification.

10 The invention relates to anticreeping devices of that class in which the rail is held to a tie-plate by the engagement of a rolling member in an angular space between the base-flange of the rail and an angular face 15 on an adjacent lug secured to the tie-plate, and the object of the invention is to provide simple, reliable and economical means for holding the rolling-member against upward movement and consequent escape vertically 20 from such angular space.

The invention consists in certain novel features and details of construction and arrangement by which the above objects are attained, to be hereinafter described and 25 claimed.

The accompanying drawings form a part of this specification and show an approved form of the invention.

Figure 1 is a plan view showing a portion 30 of a rail supported upon and engaged with a tie-plate. Fig. 2 is a corresponding vertical section, partly in elevation, the plane of section being indicated by the line 2—2 in Fig. 1. Fig. 3 is a top view of the rolling member alone, and on a larger scale. Fig. 4 is a corresponding side elevation.

Similar letters of reference indicate the same parts in all the figures.

40 A is the head of the rail and A¹ A² the base-flanges thereof, supported on a tie-plate B secured to a tie, not shown, by spikes D or other suitable fastening means.

45 On the upper face of the tie-plate at one end is an abutment B¹ against which lies the outer flange A¹ of the rail, and on the opposite end is a lug B² having its face nearest the rail vertical and inclined angularly toward the edge of the flange A². Its face is preferably inclined in opposite directions 50 from the center line of the lug to form on the latter an obtuse angle as indicated by the inclined faces at b b in Fig. 1. In the upper face of the tie-plate between the lug

B² and the rail, is a shallow recess b¹ extending a short distance beneath the flange A² 55 and shown as having a width equal to the length of the lug B².

In the angular space above described between the lug and the rail is received a rolling member arranged with its axis vertical, 60 the main portion or body E preferably cylindrical and having at its base a flat toe or flange E² projecting from one side, which is adapted to lie in the recess b¹ and project beneath the adjacent base-flange A². The 65 body E is preferably toothed or corrugated in the axial direction as at E¹ to engage the edge of the flange A² and one of the angular faces b of the lug, and is adapted to be crowded into the gradually narrowing angular space by the endwise movement or 70 creep of the rail until it reaches a point at which further movement in that direction is impossible and the rail is thus held and locked to the tie-plate against further advance relatively thereto.

The rolling member is held against vertical movement or displacement by the engagement of the flange E² beneath the base-flange A² of the rail, and by properly proportioning the body E and the angular faces b b of the lug the body portion will rotate but slightly before the locking position is reached and the rail and lug firmly engaged before such rotation brings the flange E² 85 into interfering contact with the lug.

An advantage of the invention is that the recess b¹ and lug B² with its angular faces may be completed in the rolling operation by which the tie-plate is formed, and further treatment of the latter by milling or otherwise, to provide means for holding the rolling member E E² against vertical displacement relatively to the base-flange and lug, is avoided, thus materially reducing the 95 cost of manufacturing the tie-plate.

The flange E² is shown as circular and eccentric to the body E but the shape and location of such flange may be varied as found necessary or desirable in adapting the invention to the conditions under which it may be called upon to serve.

The double angularity of the faces of the lug B² prevents the release of the rolling member by a reverse movement of the rail 105 and also serves to hold the latter against

creep in either direction. A single inclined face will serve successfully in holding the rail against creeping strains in one direction.

I claim:—

- 5 In a device of the character set forth, a tie-plate adapted to support a rail and having a recess in its upper face, a lug on said plate having an angular face adjacent to such rail, a rolling member having a body portion received in the angular space between said angular face and rail and engaging said lug and the base-flange of such rail, and having a flange projecting from one side

only of said body portion, said flange received in said recess and extending beneath 15 the base-flange of the rail to engage the latter and prevent vertical movement of said rolling member.

In testimony that I claim the invention above set forth I affix my signature, in presence of two witnesses.

EDMUND B. POWERS.
